HAIR WAVING AND CURLING DEVICE

Nellie C. McCloskey, Philadelphia, Pa.

Application April 2, 1935, Serial No. 14,208

8 Claims. (Cl. 132—41)

My invention relates to improvements in hair curling and waving devices, and has for an object the provision of a device which is extremely simple in construction and operation, and yet which can be used for curling and waving the human hair and because of its construction will give to the hair an appearance of natural curliness inasmuch as the hair will be curled in a plurality of directions rather than in only one direction or plane, as is the case with the known types of curling and waving devices.

Another object is the provision of a device which will accomplish the above objects without the use of heat and may be used with the ordinary, well known hair dressing or lotion.

Another object is the provision of a device which is relatively inexpensive, and is also light and compact, and when properly positioned, will stay in place until removed. In accomplishing this latter object, I preferably employ clamping members which are provided with means for preventing the displacement of the hair from the position desired and in which position it is placed when the device is applied.

Other objects will appear hereinafter.

My invention, therefore, comprises a hair curling and waving device which has a supporting frame, a pair of clamping members pivotally supported by said frame and adapted to be moved toward and from each other in order to grip securely the inserted hair, a pair of wave forming members arranged and supported relative to said supporting frame so as to be movable longitudinally of each other, and having appropriate means for preventing displacement of the hair after positioning, and lastly, means for effecting longitudinal movement of the wave-forming devices with respect to each other as the clamping members are brought together.

My device may be best understood by reference to the accompanying drawing, in which:

Figure 1 is a side elevational view of my device with one of the clamping members moved upwardly and shows in dotted lines the position of the other clamping member when moved from the position it occupies in Figure 1.

Figure 2 is a side elevational view of my device taken from the side opposite that shown in Figure 1 and shows the various parts in closed or clamped relation.

Figure 3 is a top plan view of the device in open position, as shown in Figure 1.

Figure 4 is a top plan view of the device in its closed or clamped position, such as that shown in Figure 2.

Figure 5 is a perspective view of the supporting frame,

Figure 6 is a perspective view of the wave-forming member movement actuating member,

Figure 7 is a detail view showing one of the gripping devices used on one of the wave-forming members,

Figure 8 is a detail view illustrating one of the wave-forming members,

Figure 9 is a diagrammatic view illustrating substantially in section the relation of the parts after the clamping members have been closed for use,

Figure 10 is a detail view of the gripping devices employed on the other of the wave-forming devices, and

Figure 11 is a detail view illustrating one of the wave-forming devices upon which the gripping devices of Figure 10 are employed.

Figure 12 is a view similar to Figure 7 but looking in the direction at right angles thereto, Figure 13 is a plan view of the part shown at Figure 8, and Figure 14 is a plan view of the part shown at Figure 11.

Referring now to the drawing, my device comprises a frame or supporting member 15 which has a pair of spaced parallel base members 16 joined by a U-shaped yoke 17, and a pair of vertically extending pivot supporting legs 18 with pin supporting openings 19 thereon.

An upper clamping bar 20 is formed of an elongated substantially arcuate shape strip 21 having a pair of depending flanges 22 adjacent one end thereof, which are provided with pivot pin receiving openings and having a depending catch member 23 adjacent the opposite end of bar 20. A lower clamping member 24 is formed of an elongated arcuate strip and has an upturned flange 25, preferably formed integrally therewith, which is likewise arcuate in elevation.

Adjacent one end of the flange 25 an appropriate pivot pin receiving opening is provided and a longitudinally extending catch lug 26 is provided at its opposite end for cooperation with catch 23.

The upper clamping member 20 and the lower clamping member 24 are supported between the upstanding legs 18 of frame 15 and are held in place by an appropriate pivot pin 27 which passes through the pivot pin supporting openings 19 and the openings in the ends of clamping members 20 and 24.

One wave-forming member 28, which will hereinafter be called the left hand wave-forming

member, comprises an elongated strip-like arcuate shape base 29, which has an upstanding flange 30 formed integrally therewith, and which is substantially arcuate in elevation also. A plurality 5 of spacing teeth 31 are formed in base 29 and these teeth extend downwardly or in the opposite direction from upturned flange 30. Preferably, teeth 31 are relatively closely spaced and are formed in base 29 by appropriate punches and 10 dies. Adjacent the ends of base 29 are secured a pair of U-shaped slide straps 32 and these may be secured to base 29 preferably after assembly of the various parts.

An upstanding U-shaped bracket 33 is secured 15 intermediate the ends of base 29, but preferably closer to one end than the other, for purposes to be later described.

Wave-forming member 34, which will herein-after be called the right hand wave-forming de- 20 vice, comprises generally an elongated strip-like base 35 of a generally arcuate shape in elevation and is provided with a depending flange 36, which is preferably serrated to provide spacing teeth 37. In elevation the lower extremities of the teeth 37 25 are arranged on an arc which is substantially concentric to the curvature of base 35. An up-standing flange 38 is preferably formed integrally with base 35 and is also arcuate in elevation. A pair of slide straps 39 are preferably secured to 30 base 35 adjacent its opposite ends and an up-standing U-shaped bracket 40 is preferably secured to base 35 intermediate its ends but adjacent its right end, as shown in Figure 1, or opposite the end of wave-forming member 28, which is 35 provided with U-shaped bracket 33.

A wave-forming member movement actuating member 41 comprises a spanning base 42 formed preferably of spring metal, and a pair of depend- 40 ing spaced legs 43 with curled bracket gripping ends 44 formed at their lower extremities. The base 42 of member 41 is provided with appropriate rivet openings, and the base is preferably riveted to clamping bar 20, as shown clearly in Figure 1.

The assembly of my complete device may be 45 effected as follows: The upstanding legs 18 of supporting frame 15 may be slid through brackets 33 and 40, and thus wave-forming members 28 and 34 will be supported by the base members 16 of frame 15. Thereafter, one end of flange 25 50 of clamping member 24 may be placed between pivot pin supporting openings 19 of upstanding legs 18 so that the pivot pin receiving opening of flange 25 is in registry with the pivot pin sup- 55 porting openings 19. Then the depending flanges 22 of upper clamping bar 20 may also be placed so that their pivot pin receiving openings are in 60 registry with pivot pin supporting openings 19, and pivot pin 27 may then be inserted in the aligned openings so as to secure together pivotally lower clamping member 24, upper clamping mem- 65 ber 20, and supporting frame 15.

As heretofore described, the wave-forming member movement actuating device 41 is riveted to upper clamping bar 20. The lower curled ends 65 of depending legs 43 may then be caused to embrace brackets 33 and 40. The slide straps 32 and 39 may then be placed on their respective bases 29 and 35, and riveted in place so as to hold in sliding engagement the bases 29 and 35 to the 70 bases 16 of supporting frame 15.

The operation of the device is as follows: When 75 it is desired to use my device, the catch 23 is released from lug 26 and the upper clamping bar assumes the position shown in Figure 1, and the lower clamping bar may be dropped to the posi-

tion indicated in dotted lines in the same figure.

Thereafter, the hair may be laid over the upper edges of flange 25 in the manner indicated in dotted lines in Figure 9, and the various spacing teeth 31 may be caused to separate the hair close to the head, or close to another similar device between the head and teeth 31 in much the manner in which the teeth of a comb separate the hair. Likewise, the spacing teeth 37 will separate the hair adjacent the outer edge of wave-forming member 34. After the hair has been properly spaced, the lower clamping member 24 and upper clamping member 20 are brought together in the position indicated in Figure 2, and catch 23 is engaged by lug 26. During the closing of the two 15 camping members it can be seen that the depending legs 43 of device 41 will cause longitudinal movement of wave-forming members 28 and 34 relative to each other, and they will be brought from the positions indicated in Figure 3 to the 20 positions indicated in Figure 4. This will cause what might be termed a lateral waving of the hair, and the further closing of the device will cause the flange 25 of clamping bar 24 to be forced upwardly between the spaced flanges 30 and 38 of 25 wave-forming members 28 and 34, respectively, and give to the hair what might be termed a vertical wave. Thus the result, after permitting the device to remain in position for an appropriate length of time, will be that the hair is 30 given an appearance of natural waviness.

Preferably, my device is formed of relatively light metal and for some of the parts an aluminum alloy may be employed. As before stated, the wave-forming member movement actuating 35 device 41 is preferably formed of spring metal, and obviously clamping members 20 and 24 should be of sufficient strength to withstand the ordinary usage to which my device is put.

While I have shown and described my preferred 40 form of construction, I do not wish to be limited to the details herein shown and described, but wish to avail myself of all variations coming with-in the scope of the appended claims.

I claim:—

1. A device of the character described comprising a supporting frame, a pair of clamping members pivotally secured to said frame, a pair of wave-forming members slidably supported by said frame and arranged between said clamping members, hair spacing members formed on said wave-forming members, and means for moving said wave-forming members longitudinally of each other, said last mentioned means being operable by one of said clamping members as said 50 clamping members are brought together in clamp- 55 ing position.

2. A device of the character described comprising a supporting frame, a pair of clamping members pivotally carried by said frame, an up-standing flange carried by one of said clamping members, a pair of spaced wave-forming members slidably supported by said frame, hair spacing members carried by said wave-forming mem- 60 bers, means for causing longitudinal sliding movement of said wave-forming members relative to each other, said upstanding flange on one of said clamping members being adapted to be pressed into the space between said wave-forming members and the other of said clamping members being adapted to cause the actuation of said means for effecting longitudinal sliding movement of said wave-forming members when said clamping members are brought together into clamping position.

3. A device of the character described comprising a supporting frame, a pair of clamping members pivotally secured to said frame, a pair of wave-forming members slidably supported by said frame and arranged between said clamping members, hair spacing members formed on said wave-forming members, means for moving said wave-forming members longitudinally of each other, said last mentioned means being operable by one of said clamping members as said clamping members are brought together in clamping position, and catch means for holding said clamping means together. 5
4. A device of the character described comprising a supporting frame, a pair of clamping members pivotally carried by said frame, an upstanding flange carried by one of said clamping members, a pair of spaced wave-forming members slidably supported by said frame, hair spacing members carried by said wave-forming members, means for causing longitudinal sliding movement of said wave-forming members relative to each other, said upstanding flange on one of said clamping members being adapted to be pressed into the space between said wave-forming members and the other of said clamping members being adapted to cause the actuation of said means for effecting longitudinal sliding movement of said wave-forming members when said clamping members are brought together into clamping position, and catch means for holding said clamping means together. 10
5. A device of the character described comprising a supporting frame, a pair of clamping members pivotally supported by said frame, a pair of wave-forming members slidably supported by said frame between said clamping members, hair spacing members carried by said wave-forming members, and means for effecting longitudinal movement of said wave-forming mem- 15
- bers in opposite directions when actuated, said last mentioned means being actuated when said clamping members are brought together into clamping position. 5
6. A device of the character described comprising a supporting frame, a pair of clamping members pivotally supported by said frame, a pair of wave-forming members slidably supported by said frame between said clamping members, hair spacing members carried by said wave-forming means, means for effecting longitudinal movement of said wave-forming members in opposite directions when actuated, said last mentioned means being actuated when said clamping members are brought together into clamping 10 position, and catch means for holding said clamping members in clamping position. 15
7. A hair waving device of the character described comprising a pair of clamping members, a pair of waving members associated with the clamping members and formed with hair spacing means, and operating connections between the wave forming members and one of the clamping members whereby relative movement of the clamping members causes relative longitudinal 20 movement of the wave forming members. 25
8. In a hair waving device of the character described, the combination with a pair of clamping members pivotally connected at one end and adapted to move toward and away from each other on said pivot, of a pair of wave forming members, hair engaging teeth on said wave forming members, and links connecting each of said wave forming members to one of the clamping members whereby movement of the said clamping members toward the other clamping member causes relative longitudinal movement of the wave forming members. 30 35
